UNITED STATES PATENT OFFICE.

MILON J. TRUMBLE, OF LOS ANGELES, CALIFORNIA, ASSIGNOR TO SIMPLEX REFINING COMPANY, A CORPORATION OF CALIFORNIA.

PROCESS OF TREATING PETROLEUM.

1,262,875.

Specification of Letters Patent. Patented Apr. 16, 1918.

Application filed October 10, 1910. Serial No. 586,382.

To all whom it may concern:

Be it known that I, MILON J. TRUMBLE, a citizen of the United States, residing at Los Angeles, in the county of Los Angeles and State of California, have invented a new and useful Process of Treating Petroleum, of which the following is a specification.

This invention relates to a process for the treatment of hydrocarbon oils or petroleum to separate the lighter or more volatile constituents therefrom, the process being particularly intended for so treating the crude oil as to remove and save the gasolene and other light volatile products.

The main object of the invention is to provide a process whereby the above described vaporization or separation may be effected in the most rapid, economical and efficient manner.

Another object of the invention is to provide a process whereby such separation may be effected in an apparatus of extremely limited size compared to the apparatus generally used for such purposes.

The process consists essentially in heating the oil in a closed receptacle to a temperature above the boiling point of the lighter constituents of the oil for the pressure at which they are to be vaporized, the oil being maintained while it is being heated at such pressure as to prevent vaporization during the heating operation, then allowing the heated oil to pass into a vaporizing chamber where the lighter constituents of the oil immediately expand and pass into a state of vapor or gas by reason of the temperature thereof being higher than the boiling point for the pressure in said vaporizing chamber, and withdrawing said vaporized or gasified products from the vaporizing chamber. The process further comprises in the vaporizing operation exposure of the oil in a thin film or layer to the action of a heated surface, thereby expediting the separation of the volatile constituents from the heavier constituents and withdrawing the vaporized constituents as fast as they are released from such film or layer.

Other objects and advantages of the process will appear hereinafter.

The accompanying drawings illustrate an apparatus or vaporizer suitable for carrying out the invention, and referring thereto:

55

Figure 1 is a vertical section of a vaporizer showing the form thereof which I consider best adapted for carrying out the process.

Figs. 2, 3 and 4 are sectional views showing modified forms of vaporizers which may be used in carrying out the process.

Referring to Fig. 1, the apparatus comprises a furnace or heating chamber 1 provided with a fire box or combustion chamber 2 for generating heat therein and with a stack or chimney 3. In said heating chamber is provided a heating coil 4, said coil being of sufficient length and capacity to retain the body of oil therein for a considerable time in heat absorbing relation with the heating chamber. This coil 4 is supplied with oil at one end thereof by a supply pipe 5 having an inlet valve 6, said supply pipe communicating with regenerating

75

means for heating the oil as it is supplied to the coil by means of heat absorbed from the out-going products of the process. At the end of the coil 4 which is farthest from the inlet pipe 5, a drainage pipe 8 is provided having a draw-off cock 9, the coil 4 inclining continuously from the inlet end to the said farther end, so that any water separated from the oil while in said coil collects at said drainage pipe and may be

80

drawn off from time to time. A pipe 10 extends upwardly from the coil near the end which is farthest from the inlet end of the coil, said pipe extending to the top of a vaporizing chamber 11 which is formed in

90

Fig. 1 as a vertical cylinder inclosed within the stack 3, so that the walls of said cylinder are heated by the hot gases passing upwardly through said stack. A valve 12 is provided in said pipe 10 to hold the oil under pressure in coil 4 and to control the supply of oil to the chamber 11, said valve having an operating handle 13. From the lower end of the vaporizing chamber 11 extends a drainage pipe 15 for residual oil,

95

said drainage pipe having an outlet valve 16 which is adjusted in position to maintain a

100

- 2
- body of oil in the drainage pipe 15 and in the lower part of the vaporizing chamber 11, as shown in Fig. 1, so as to form a liquid seal at the bottom of said chamber and prevent 5 vent outflow of vapor therefrom, except through the vapor outlets and vapor line, as hereinafter set forth. For showing the level of the oil in the vaporizing chamber pet-cocks 17' may be provided on a vertical pipe 17 connected near its upper and lower ends by pipes 18 to the vaporizing chamber 11.
- Valve outlet means are provided at distributing points or heights in the vaporizing chamber 11 to take off the vapor as fast as it is liberated and deliver it to the vapor line indicated at 20, the end of said vapor line extending vertically alongside the stack and having a plurality of tubes 21 extending 10 therefrom into the vaporizing chamber 11 and communicating at their inner ends with a vertical pipe or chamber 22, having a series or plurality of perforated portions 23 for passage of the vapor into said chamber 25 22 from the chamber 11. At the top of the pipe or chamber 22 is provided a cone-shaped spreader 25, the apex of which is located directly beneath the outlet of the supply pipe 10 and the rim of which extends 30 close to the wall of the vaporizing chamber 11, so as to spread the oil issuing from the pipe 10 over the walls of the chamber in a thin film. Directly beneath the connection for each of the vapor outlet pipes 21 to the 35 vertical chamber 22, a skirt or obliquely downward extending flange 26 is provided on said pipe 22 whose rim extends in proximity to the wall of the chamber 11 to cause any unvaporized oil flowing on said skirt to 40 be deflected outwardly and brought in contact with the outer wall of the vaporizing chamber in a thin film. The perforations 23 in the vertical chamber 22 which provide for efflux of vapor from the chamber 11 are located 45 directly beneath and within the respective conical spreading means 25 and 26, and the said vertical chamber or pipe 22 is open at the bottom so that the vapor generated in the chamber 11 may pass into the 50 pipe 22 at the bottom thereof and through all of the perforations 23 therein, the vapor being thereby removed from the oil as rapidly as it is generated. The vapor line 20 leads through condensing means which also 55 form part of the regenerative system for supplying heat to the incoming oil, said line 20 extending through a jacket tube 28, the oil being supplied under pressure at one end of said tube by a pipe 29 into which the oil 60 is pumped by a pump 30, the other end of said jacket tube 28 being connected by a pipe 31 to one end of a tube 32 surrounding the residual outlet pipe 15, the further end of said jacket tube 32 being connected to the

oil supply pipe 5 for the heating coil 4. 65 Valves 34, 35 may be provided respectively in the vapor line and in the delivery line for the condensate.

The process is carried out as follows in the above described apparatus: The valve 12 70 is partially closed and oil is pumped in at the pressure required in the heating operation, say, three or more pounds per square inch according to the required temperature and is maintained through the regulation 75 of such valve 12. The oil in entering passes in through pipe 29, through jacket 28, pipe 31, jacket 32 and pipe 5 to heating coil 4, said heating coil being of sufficient length and area to enable the heating or furnace 80 chamber 1 to supply the required amount of heat to said coil in the continuous passage of the oil from one end of the coil to the other to vaporize the product desired to be taken off. The said oil has a slow movement and 85 a continual increase of temperature from the inlet to the delivery point. In this heating of the oil a portion of the water is released or separated therefrom, if such is held in suspension in the oil, and tends to settle in 90 the lower end of the coil, being drawn off when required through the valve 9. The heated oil passes upwardly through pipe 10 and valve 12 and in passing into the vaporizing chamber 11 is subject to a sudden expansion by reason of the lower pressure in 95 said chamber and in this expansion the lighter constituents of the oil, namely, gasoline, kerosene, etc., are suddenly passed into the form of vapor or gas. As the oil falls 100 onto the successive conical members or spreaders 25 and 26, it is directed thereby into contact with heated walls of the chamber 11, the heat supplied through said walls maintaining the temperature sufficient to 105 cause such lighter products to be boiled or evaporated from the oil and the oil being maintained in a thin layer or film on said walls, so as to present a maximum surface 110 for evaporation and facilitate the immediate release of the vapor or gas from the liquid. As fast as such vapor or gas is formed it is withdrawn or passes out through the perforations 23, outlet pipes 21 and vapor line 20 to the condenser pipe 27. The process 115 may be carried out in any apparatus adapted to provide for heating of the oil under pressure and then subjecting it to sudden expansion on lowering the pressure, so as to cause sudden release of the lighter 120 products therefrom in the state of gas or vapor.

Thus, Fig. 2 shows another form of vaporizing chamber which may be used, said vaporizing chamber consisting of an inverted conical chamber 36 in the stack 3', said chamber having an outlet 37 at its lower end for residuum oil and provided at its upper

end with spreaders 38 and a supply pipe 39 having perforations 40 and a controlling valve 41, vapor outlet pipes 42 being provided at different heights within the vaporizing chamber 36 and connected to the vapor line 43.

Fig. 3 shows another form of vaporizing chamber which may be used consisting of a box or casing 46 having an inclined wall 46' 10 on which the oil descends in a thin layer from a spreader plate 47, the oil being supplied to said plate by a supply pipe 48 provided with a valve 49. A residuum outlet pipe 50 is provided at the lower end of said 15 casing 46 and vapor outlet pipes 51 are provided at different heights in said casing connected to the vapor line 52.

In Fig. 4, the vaporizing chamber is shown as a semi-cylindrical vessel 54 stored 20 within a combustion chamber 55 and having an oil supply pipe 56 at each side, said pipes being perforated as at 56' to allow the oil to run down the inclined wall at each side 25 of said vessel 54 and a vapor outlet 58 being provided at the top of said vessel. 59 is a valve controlling the supply of oil and 60 is an outlet for the residuum.

In each of the expanding chambers shown, provision is made for causing the oil to run 30 in a thin layer or film on a heating surface, the said surface in Fig. 1 being the walls of the vertical chamber 11 and the said surfaces in Figs. 2, 3 and 4 being the inclined walls

of the respective vaporizing chambers there-
in shown.

35

What I claim is:

1. The process of separating hydro-carbon vapors from a mixture of hydro-carbons, which consists in heating the mixture under pressure at a temperature sufficient to cause 40 vaporization of the lighter constituents at atmospheric pressure, releasing the pressure to cause vaporization of the lighter hydro-carbons, and simultaneously spreading the unvaporized portions of the mixture in a 45 thin film and permitting the vapors to readily escape.

2. The process of separating hydro-carbon vapors from a mixture of hydro-carbons, which consists in heating the mixture under 50 pressure to a temperature sufficient to vaporize the lighter constituents at atmospheric pressure, releasing the pressure so that hydro-carbon vapors can be readily given off simultaneously with said release, 55 spreading the unvaporized portions in a thin film, and simultaneously applying heat to said film to supply the latent heat absorbed by said vapors.

In testimony whereof, I have hereunto set 60 my hand at Los Angeles, California, this 3rd day of October, 1910.

MILON J. TRUMBLE.
